UNITED STATES PATENT OFFICE.

THOMAS MATHEWS, OF LEICESTER, ENGLAND.

TOY, KINDERGARTEN APPLIANCE, AND THE LIKE.

1,333,181.

Specification of Letters Patent. Patented Mar. 9, 1920.

Application filed July 31, 1918. Serial No. 247,532.

To all whom it may concern:

Be it known that I, THOMAS MATHEWS, subject of the King of Great Britain, residing at Leicester, in the county of Leicester, England, have invented certain new and useful Improvements in or Relating to Toys, Kindergarten Appliances, and the like, of which the following is a specification, reference being had therein to the accompanying drawing.

This invention relates to toys, kindergarten appliances and the like, and concerns those of the kind made of cardboard or similar material and constructed to fold or collapse to a substantially flat or compact condition when not in use.

The invention comprises a scenic base or background with or without some collapsible structure thereon, and a number of subsidiary devices to be used in conjunction with the said base or back as will be herein-after described.

The novelty of the invention resides more particularly in the character and formation of the subsidiary devices. These consist of figures (such as animals, trees and the like) cut out in the flat and printed or otherwise got up on both sides so as to be reversible, two or more of such figures being connected together by means which allow them to lie close together face to face in a collapsed condition and also admit of limited separation of said connected figures whereby they are rendered capable of standing erect.

A further feature of the said subsidiary devices may be that the connected figures differ from each other, such for instance as regards attitude, shape and so on, the purpose of this being that one side of such device will give a different effect from the other and thus enable the general effect obtained by the whole of the devices to be varied.

The limited separation of the connected figures to bring the devices into a self supporting condition disposes one figure in front of another and thus a relief effect is obtained when such devices are in use.

Or instead of the figures being connected together in pairs or more I may arrange for them to be used separately, in which case the individual figures will have combined with them a supporting device such as a small wire clip which when applied to the lower edge will enable the figure to stand alone. Such separate figures will however,

still retain the before mentioned characteristic feature of reversibility.

In further describing the invention reference will be made to the accompanying drawing wherein a concrete example in the form of a Noah's ark toy is illustrated.

In the drawing referred to:—

Fig. 1 is a perspective view of the foldable and collapsible main part of the toy in its opened and erected position.

Fig. 2 is a plan and

Fig. 3 is an end view of the rear part of same.

Fig. 4 is a perspective view of a pair of connected subsidiary devices.

Fig. 5 is a similar view showing the reverse side of the same devices.

Figs. 6 and 7 show in perspective other examples of the connected subsidiary devices.

Fig. 8 shows a form of the separate device for individual use.

Fig. 9 is a perspective view of a convenient form of wire clip for use on the separate device as shown in Fig. 8 to enable it to stand alone.

In the example shown the main part of the toy comprises (Figs. 1, 2 and 3) a suitable base 1 and back-ground 2 combined with which is a collapsible structure representing a Noah's ark.

The background 2 is hingedly connected to the base member 1 at 3 and is adapted to assume an upright position in use as shown and turn downward in the direction of the arrow Fig. 3 and lie flat with the base. This vertical back member 2 constitutes the back of the collapsible structure, the front of the latter being formed by another vertical member 4 hingedly attached to the base 1 at 5 and also adapted to fold down flat in a similar manner to the back. The vertical back member 2 and vertical front member 4 are connected at the top by a roof member 6 which is hingedly attached to said members at 7 and 8 respectively and is centrally scored or hinged in a longitudinal direction at 9 so that it may be bent upward to an angular position as indicated when the structure is erected but is able to assume a flat condition when the structure is collapsed.

Hingedly secured at 10 to the sides of the front member 4 are end pieces 11 which may be turned to a position at right angles to the front as shown to form closed ends to

the structure and maintain the latter in the erected position, the said end pieces being formed with sloping top sides 12 to fit underneath the roof member 6 and determine its angular shape. By pulling out the end pieces 11 (in the direction indicated by arrows in Fig. 2) into alignment with the front member 4 the whole structure including the back 2 can be turned down forwardly (as indicated by the arrows in Fig. 3) and caused to assume a flat condition on the base 1. The end pieces 11 may have holes 13 therein for the insertion of the finger to pull them outward.

15 The base member 1 is hinged at 14 (Fig. 1) whereby the forward part 1^a of same can be folded backward (as indicated by the arrow) underneath the part 1 to reduce the base to a small compass.

20 The base 1, 1^a, back 2 and collapsible structure are appropriately printed, shaped and got up to represent parts in general accordance with the scheme being carried out.

25 For use with a main part such as just described, some of the subsidiary devices may represent animals such as shown in Figs. 4 and 5 while others represent pieces of scenery and trees as in Figs. 6 and 7 or characters as shown in the example Fig. 8. The 30 figures or parts 15 constituting the subsidiary devices are cut out of cardboard and are printed or otherwise got up similarly on both sides so as to be reversible as represented by Figs. 4 and 5 which show respectively the opposite sides of the same device.

35 The subsidiary devices may as shown in Figs. 4 to 7 be composed of a number of the figures or parts 15 connected together, for instance the figures or parts may be connected in pairs as in Figs. 4, 5 and 6, or three figures or parts may be connected as represented in Fig. 7 to constitute the device. In some cases more than three parts 45 may be connected, or on the other hand the figures may be used separately as in Fig. 8.

40 Conveniently when two or more figures or parts 15 are connected together to constitute a subsidiary device, the connecting means consists of an intermediate folding distance piece 16 whose sides form a parallelogram such as shown in Figs. 4 to 7. This may be made of cardboard scored and bent vertically so that each corner 17 forms a hinge. The figures or parts 16 are secured to opposite sides of the parallelogram and are thus maintained in parallel relationship while at the same time they can be brought together and moved apart by bending the piece 16 on its hinged corners 17. Or instead of connecting the parts 15 by a complete four sided piece such as 16 the figures may be connected by a pair of distance pieces (not shown) consisting of parallel strips hingedly attached at their opposite

ends to the opposing sides or faces of the figures. Two or more figures connected in the manner described so as to be capable of folding flat together and also of being separated to a limited extent whereby they are rendered self supporting such figures being similarly printed on both sides so as to be reversible, form very effective subsidiary devices for the purpose in view seeing that in use, *i. e.*, when erected they stand away from each other in relief and owing to their reversibility can be positioned with either side to the front or viewed from either side. Further, by using subsidiary devices wherein the connected figures differ from each other, such as regards attitude, shape and so on as shown in Figs. 4 and 5, a more varied effect is obtained when the device is reversed.

45 With regard to the single reversible figures (Fig. 8) these may be supported by a simple form of wire clip or stand 18 such as shown in Fig. 9.

50 The cardboard figure or character 15 fits between the vertical limbs 19 the forwardly and rearwardly extending legs 20 being disposed horizontally and serve to keep the figure upright when its lower edge is placed upon the base 1. The said lower edge may be notched at 21 to receive the end 22 of the loop of wire or the clip may be placed on the figure in such a position that the end 22 will be situated at the side instead of underneath the figure.

55 It will be apparent that the main part 100 and subsidiary devices constructed as herein-described lend themselves to being printed or otherwise got up in other ways than that indicated. For instance the main part may be got up to represent a farmhouse and 105 farmyard or according to another embodiment it may represent a jungle scene, the subsidiary devices for use with these parts being of appropriate character. By suitably shaping and getting up the parts composing 110 the complete toy or appliance a variety of different subjects may be carried out with effective results.

60 In some cases the collapsible structure may be omitted from the base and instead a 115 suitably printed and shaped member such as the front member 4 may be used, this being connected with the background member by hinged strips or distance pieces. Or again a base member such as 1, 1^a may be 120 used without a background or collapsible structure.

65 I am aware that reversible figures cut from flat material have previously been proposed and that it has also been suggested 125 to connect the parts of figures cut from flat material by hinged strips so as to allow them to fold into flat form.

70 What I claim then is:—

75 A toy, kindergarten appliance or the like,

comprising a scenic base, a background hingedly attached thereto, a collapsible structure combined with said base and background and consisting of a vertical front 5 member hingedly attached to the base, roof members hingedly connected together and hingedly attached to the front and background members, and hinged end pieces to close the ends of the structure, said base, 10 back ground and collapsible structure being adapted to open to an erected form for use and to close by folding to a flat condition

when not in use, and a number of subsidiary devices to be used in conjunction therewith, consisting of figures cut out in the flat and 15 of single thickness printed on both sides so as to be reversible, substantially as described.

In testimony whereof I affix my signature in presence of two witnesses.

THOMAS MATHEWS.
